DESIGN FOR A SWITCH CASING

Harold I. Nicholas, Chicago, Ill., assignor to Burke & James, Inc., Chicago, Ill., a corporation of Illinois

Application February 13, 1942, Serial No. 105,785

Term of patent 7 years

To all whom it may concern:

Be it known that I, Harold I. Nicholas, a citizen of the United States, residing at Chicago, in the county of Cook and State of Illinois, have invented a new, original, and ornamental Design for a Switch Casing, of which the following is a specification, reference being had to the accompanying drawing forming a part thereof.

In the drawing,

The side of the article which is not shown is a duplicate of that illustrated in Fig. 1.

I claim:

The ornamental design for a switch casing, as shown and described.

HAROLD I. NICHOLAS.
